BASEBOARD REGISTER

Gordon Bennett, West Hartford, Conn., assignor to The Vulcan Radiator Company, Hartford, Conn.

Application December 17, 1954, Serial No. 33,594

Term of patent 14 years

(Cl. D81—21)

Fig. 1 is an isometric view of a baseboard register embodying my new design.

Fig. 2 is a top plan view of the register in a longer length than shown in Fig. 1 and with portions broken away to indicate indeterminate length.

Fig. 3 is a cross-sectional view taken on line 3—3 of Fig. 4.

Fig. 4 is a front view of said register.

I claim:

The ornamental design for a baseboard register, substantially as shown.
